GROUND EFFECT MACHINE

William R. Bertelsen, 4343 18th Ave.,
Rock Island, Ill. 61201

Filed Sept. 24, 1968, Ser. No. 13,688

Term of patent 14 years

Int. Cl. D12—07, 08

U.S. Cl. D71—1

FIGURE 1 is a perspective view of a ground effect machine incorporating the design of the present invention.

FIGURE 2 is a front view of the design of FIGURE 1.

FIGURE 3 is a rear view of the design of FIGURE 1.

FIGURE 4 is a side elevational view of the design of FIGURE 1.

FIGURE 5 is a top view of the design of FIGURE 1.

The bottom of the ground effect machine is not seen when in use. The dotted line showings also form no part of this invention and are for illustrative purposes only.

I claim:

The ornamental design for a ground effect machine, as shown and described.
